[57] CLAIM

The ornamental design for a storage tray for printwheels, as shown and described.

DESCRIPTION

FIG. 1 is a perspective view of a storage tray for printwheels showing my new design, with the cover partially open;

FIG. 2 is a top plan view thereof with the cover and latch closed;

FIG. 3 a top plan view thereof with the cover and latch fully open;

FIG. 4 is a front elevational view thereof with the cover and latch fully open;

FIG. 5 is a front view thereof with the cover and latch closed;

FIG. 6 is a right side elevational view with the cover and latch closed; and

FIG. 7 is a perspective view of another embodiment of a storage tray for printwheels showing my design, with the cover partially open.

The surfaces disposed downward in FIGS. 2, 5, 6 and 7 are plain and unadorned.
